Guy F. Chesney,

INVENTOR

BY *Victor J. Evans*

and A. R. Evans ATTORNEY

P. Hickey.

WITNESS:

UNITED STATES PATENT OFFICE

GUY F. CHESNEY, OF SPARTANBURG, SOUTH CAROLINA.

CORD FASTENER

Application filed December 22, 1930. Serial No. 504,172.

This invention relates to improvements in quick detachable cord fasteners and has for the primary object, the provision of a device of the above stated character whereby a wrapping or securing cord for packages and like articles may be easily and quickly secured about the package without forming or tying knots in the cord and which will permit the cord to be easily and quickly removed with the cord and fastener ready for further use, thereby providing a large saving in wrapping cord over the now customary practice employed on packages wherein the cord is tied in various ways and which usually requires severance of the cord to remove the latter from a package and rendering the cord unfit for further use.

Another object of this invention is the provision of a cord fastener of the above stated character which will be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the accompanying drawings and the following description, in which—

Figure 1 is a front elevation of a cord fastener constructed in accordance with my invention and showing the same applied to a package.

Figure 2 is an edge elevation illustrating the same.

Figure 3 is an end view showing certain of the grooves for receiving the cord.

Figure 4 is a sectional view illustrating the position of the cord within the various grooves.

Figure 5 is a perspective view illustrating the fastener of the cord removed.

Referring in detail to the drawings the numeral 1 indicates the body of the cord fastener which may be of any desired shape preferably of rectangular formation as shown in

the drawing with a flat rear face 2 adapted to rest against the package 3 and with a similar outer or front face 4 having grooves 5 and 6 formed therein and which grooves are arranged at right angles to each other while the groove 5 is located adjacent one end of the body and the groove 6 located adjacent one of the sides of the body and communicating with the groove 5 at one end and extending through one end of the body. The ends of the groove 5 extend through opposite sides of the body.

The body is provided with a chamber 7 communicating with the grooves 5 and 6 and providing a portion 8 between the groove 6 and chamber 7 having a rounded end 9. The walls of the chamber 7 have formed thereon intermeshing ribs 10 located wholly within the chamber 7 for the purpose of fastening the free end of a wrapping cord 11 after the same has been placed about the package 3 in the usual way. The other end of the wrapping cord 11 is secured to one end of the body 1 as at 12.

The body 1 is placed against one face of the package to be wrapped and the cord is first extended about the package in the direction indicated by the arrows in Figure 1, this positions one run of the cord in the groove 6 and through the groove 5 bearing against the rounded end 9 of the portion 8 where said run of the cord extends again about the package and enters the groove 5 as shown in Figure 1, and is brought into engagement with the rounded end 9 of the portion 8 and between the ribs 10 firmly securing the free end of the cord to the body with the runs of the cord efficiently positioned about the package.

To untie the package, it is only necessary to disengage the free end of the cord from the ribs 10 and remove the cord from the grooves 5 and 6 and the device is then ready for use on another package.

While I have shown and described the preferred embodiment of my invention, it will be understood that minor changes in construction, combination and arrangement of parts may be made without departing from the spirit and scope as claimed.

Having thus described my invention, what I claim is:

1. A cord fastener comprising a body having grooves formed in one face thereof and arranged at right angles to each other, a tying cord secured at one end to the body and passed about a package to provide several runs in the cord receivable in said grooves, and means detachably securing the free end of the cord to the body.
2. A cord fastener comprising a body having grooves formed in one face and arranged at right angles to each other and in communication with each other, a tying cord secured at one end to the body and passed about a package and through said grooves, and interlocking ribs on said body to receive the free end of the cord.
3. A cord fastener comprising a body having grooves in one face and arranged at right angles to each other and in communication with each other, said body having a chamber communicating with one of the grooves, a wrapping cord secured at one end to the body and passed about a package several times and extended through the grooves with the free end disposed in the chamber and projecting beyond one edge of the body, and staggered arranged ribs formed in said chamber to receive and grip the cord adjacent the free end.

In testimony whereof I affix my signature.

GUY F. CHESNEY.
